United States Patent

Des. 242,431
Patented Nov. 23, 1976

242,431

SIGN CLIP

Richard A. Carroll, North Providence, R.I., assignor to
The Lorac Company, Inc.

Filed Apr. 7, 1975, Ser. No. 565,757

Term of patent 14 years

Int. Cl. D8—08

U.S. Cl. D8—243

FIG. 1

FIG. 2

FIG. 3

FIG. 4

FIG. 5

FIG. 1 is a front end view of a sign clip showing my new design;

FIG. 2 is a rear elevational view thereof;

FIG. 3 is a top plan view thereof;

FIG. 4 is a bottom plan view thereof; and

FIG. 5 is an end elevational view thereof.

I claim:

The ornamental design for a sign clip, substantially as shown.
